CRASH PLANE

Peter Mayhew, Barrington, R. I.

Application August 19, 1941, Serial No. 407,423

4 Claims. (Cl. 244—2)

This invention relates to a heavier-than-air airplane of the fighting type for use in warfare for the destruction of enemy apparatus such, for instance, as battleships.

Heretofore, there has been the suicide type of attack on such objects as battleships, in which a pilot would run an airplane or boat into the enemy's battleship with the attacking carrier provided with enough explosives to damage the enemy's objects. In such an attack the person guiding such attacking plane or boat would lose his life. The loss of the pilot in this sort of warfare is a drawback and not one which is desirable.

One of the objects of this invention is to provide a crash type of warfare without the loss of the pilot.

Another object of the invention is the provision of an explosive carrier of any desired size which may be guided toward an object to be attacked by an auxiliary airplane releasable from the main explosive carrier, after the direction of the carrier has been provided for, that the pilot who directs the same may get away in the auxiliary plane while the main carrier will maintain its course through gyroscopic control into engagement with its target.

With these and other objects in view, the invention consists of certain novel features of construction, as will be more fully described and particularly pointed out in the appended claims.

In the accompanying drawing:

Fig. 1 is a top plan view of the assembly of explosive carrier and airplane;

Fig. 2 is a side elevation thereof;

Fig. 3 is a side elevation, partly in section, illustrating the auxiliary or get-away plane's attachment to the main plane in greater detail;

Fig. 4 is a sectional view of one of the controlling mechanisms;

Fig. 5 is a sectional view illustrating another of the control mechanisms;

Fig. 6 is a section on line 6—6 of Fig. 5;

Fig. 7 is a sectional view illustrating means for attaching the two separable flying units together; and

Fig. 8 is a section on line 8—8 of Fig. 7.

The impelling means for the main explosive carrier may consist of as many different impelling units as are necessary, and the amount of explosive carried may be increased in different units depending upon the size of the carrier which may be built. A complete airplane with controls will also be mounted on the carrier in a releasable manner, and there will be provided means for controlling both the carrier and the complete airplane from the latter prior to disconnection of the two while a gyroscope will be carried by the main explosive carrier for maintaining the controls in the set position after the separation of the two.

With reference to the drawings in greater de-

tail, the explosive-carrying structure is designated generally 10, as shown in Fig. 2, and the get-away complete airplane is designated generally 11. The explosive-carrying structure, by reason of the fact that it is not intended to carry a person or pilot, is thin or of shallow depth and provides small wind resistance and therefore is capable of great speed; it consists of leading wings 12 and tail wings 13 which are joined together by some connecting structure 14 such, for instance, as a shallow body which is provided with openings 15 that the pilot of the airplane 11 may look therethrough.

The leading wings 12 provide supports for a plurality of engine units 16 equipped with propellers 25 arranged in symmetrical balanced relation and also for a plurality of torpedoes or explosive units 17 also placed in symmetrical balanced arrangement and projecting beyond the forward end of the leading wings. A rudder 19 is provided, and separately operated hinged ailerons 20 are a part of the control structure. These two ailerons 20 may be operated together to serve as elevators. There will also be carried a stabilizing gyroscope 18 for maintaining the controls for the engines and other movable operating mechanism of the flying unit in desired position after the explosive carrier and airplane are separated. Also, there are struts 21 for supporting take-off wheels 22 and a strut 23 for supporting the rear wheel 24. All of this mechanism is well known in airplane apparatus and is therefore not attempted to be illustrated in detail herein.

The structure so far described might be referred to as a skeleton flying structure as it has no cockpit for the reception of a passenger or pilot.

On the body 14 at a location near the tail or trailing wing 13, I have mounted the complete airplane 11 by means of blocks 26 providing sockets 27 for each of two landing wheels 28 of the plane 11 and a block 29 recessed as at 30 for the landing wheel 31 of the auxiliary or get-away plane 11. These landing wheels have the usual truss supports 32 and 33 extending downwardly from the body 34 of the plane which has main wings 35, tail wings 36, rudder 37, cockpit, 38, engine 39, and propeller 40 all of a usual well-known type of airplane construction.

Within the body or fuselage 34 there is mounted support 41 for a U-shaped retracting member 42 which is anti-frictionally mounted on this support by rollers 43 and may be moved back and forth through link 47 and lever 44 pivoted as at 45 on the floor 46. A rod 48 is threaded as at 49 for the reception of a hand-operated wing nut 50 which through washer 51 engages the U-shaped member 42 and is provided at its lower end with a hook 52 to engage an eye 53 provided on the band 54 which extends about

the body 14 of the explosive carrier 10. This is the sole tying connection between the airplane 11 and the explosive carrier 10.

Lateral and longitudinal movement is prevented between the carrier 10 and plane 11 by reason of wheels and the blocks 26 and 29, while vertical movement is prevented by reason of the tying link 48. For disconnection of the two planes, it is merely necessary to pull forward the lever 44 permitting the wing nut and rod 48 to drop downwardly through the support 41 and through opening 55 in the floor 46 of the airplane 11.

In order to control the motors in the explosive carrier 10, I have provided an arrangement such as shown in Fig. 5, comprising a shaft 60 connected by universal joint 61 to shaft 62 and connected by universal joint 63 to shaft 64. Shaft 62 has a hand wheel 65 which, upon rotation, will rotate the shaft 64 through this universally connected link 60 so as to operate pinion gear 66 and rack 67 one way or the other to accelerate or slow down the engines 16 of the explosive carrier 10. I have shown only one such control connection, as all of these engines may be operated in unison; or I may have one of such connections for the starboard engines and another control for the port engines; or each of the engines may be individually controlled if desired. The link 60 consists of a square shaft 68 and a tube having a square bore 69 (see Fig. 6) for receiving the same telescopically so that these may pull apart for vertical separation of the plane 11 from the carrier 10.

In Fig. 4, I have illustrated a connecting shaft 70 comprising two parts consisting of a square shaft 71 and a telescoping shaft 72 having a square bore 73. The universal joint 74 connects the same to a shaft 75, and universal joint 76 connects the same to shaft 77. Operating wheel 78 may turn the shaft 77 to rotate the gear 79, and manipulate a quadrant 80 for movement of the flexible cords 81 or 82 to operate the rudder and aileron or other manipulating control mechanism of the explosive carrier 10. An indicator 83 may be provided for showing the position of the mechanism controlled. Upon separation of the carrier 11 from the plane 10, the link 70 will slide apart as heretofore explained in connection with the engine control for the explosive carrier. Several controls, one for each part to be operated, such as shown in Fig. 4 may be provided for controlling the different mechanisms of the explosive carrier; and these may be arranged for operation in unison by similar controls in the airplane 11, or may be separate therefrom. The ailerons or elevators will each have one of these controls. A gyroscope unit will be so arranged as to maintain the controls in a set position once they are manually moved to such position.

By the above arrangement the entire assembly such as shown in Figs. 1, 2, and 3 may be directed by the pilot in the cockpit 38 towards some battleship and so directed that substantially the center of the battleship at the boiler rooms will be struck. The elevation need be only a short distance above the water; and it may be that a haze or fog will exist covering the entire ship with the exception of possibly its conning towers which will be visible above the fog. The pilot of the assembly here described will thus direct this assembly toward the battleship at the correct height and then by pulling the release lever

44 separate the auxiliary or get-away plane 11 from the explosive carrier, as the separation occurs the gyroscope unit will be cut in to maintain the controls permitting the explosive carrier to travel onwardly on its course by reason of the gyroscopic controls which stay in and over pull the other controls to direct the crash against the battleship. A sufficient number of torpedoes or explosives ignitable by impact would be carried by the carrier plane, and in sufficient numbers these explosives would destroy most any object which they contact. As the armor of the ship is increased, the number of torpedoes would be increased, it being the object to provide sufficient explosive to just overcome the object against which the plane is directed. While this carrier plane will be completely destroyed, it is the optimum that the object against which it is directed will also be destroyed, while the pilot may get away in the auxiliary plane after he has directed the explosive carrier to its mark.

I claim:

1. In combination an airplane, controls therefore comprising ailerons and rudder, driving means therefor comprising a propeller and engine, a second airplane superimposed on the first airplane, detachable means for connecting said planes together, means extending from the second airplane to the first airplane for operation of the controls of the first airplane comprising members separably telescoped together with means for transmitting torque movement from one to the other.

2. In combination an airplane, controls therefore comprising ailerons and rudder, driving means therefor comprising a propeller and engine, a second airplane superimposed on the first airplane, detachable means for connecting said planes together, means extending from the second airplane to the first airplane for operation of the controls of the first airplane comprising members separably telescoped together with means for transmitting torque movement from one to the other, one of said members being universally connected at one end adjacent to one of said airplanes.

3. In combination an airplane, controls therefore comprising ailerons and rudder, driving means therefor comprising a propeller and engine, a second airplane superimposed on the first airplane, detachable means for connecting said planes together, means extending from the second airplane to the first airplane for operation of the controls of the first airplane comprising members separably telescoped together with means for transmitting torque movement from one to the other, one of said members being universally connected at one end adjacent to one of said airplanes and the other member being universally connected at its end adjacent to the other of said airplanes.

4. In combination an airplane, controls therefore comprising ailerons and rudder, driving means therefor comprising a propeller and engine, a second airplane superimposed on the first airplane, detachable means for connecting said planes together comprising a support having spaced positions a link fixed to the first plane and extending into the second plane between said spaced portions, a head on said link and a withdrawable fork between said spaced portion and head to form a lock.

PETER MAYHEW.
